UNITED STATES PATENT OFFICE

2,547,565

SPEAKER HAVING A TUBULAR POT

Donald C. Carlson, St. Paul, Minn., assignor to
 Wright Zimmerman, Inc., New Brighton, Minn.,
 a corporation of Minnesota

Application September 26, 1946, Serial No. 699,380

2 Claims. (Cl. 179—115.5)

1

My invention relates to an improvement in speakers and deals more particularly in a particular type of speaker pot designed to promote the efficiency of the apparatus.

For many years efforts have been made to improve the efficiency of the metallic pot used to conduct magnetic lines of force from one end of a speaker magnet to a point adjacent the other end thereof. The metallic pots previously used have been disadvantageous for certain definite reasons. In the first place these pots have usually been rectangular in shape. In bending the metal into rectangular form the structure of the metal is often broken at the corners, thus impeding the proper flow of electromagnetic force. Secondly these corners on the pot usually permit electromagnetic force to be emitted at the corners to decrease the effectiveness of the structure. Tests have shown that there is a considerable loss of electromagnetic force at the corners of the usual rectangular speaker pot. Furthermore the pots made in the past have usually been made in a single strip which is electrically connected at the ends thereof. A considerable loss of magnetic force is usually experienced between the ends of the strip, thus also decreasing the efficiency of the speaker.

Efforts have been made to weld the ends of the strip to provide a better electrical connection between the adjacent ends of the strip. This welding operation has often resulted in a change in the metallic structure of the strip tending to impede the passage of magnetic waves. Attempts have also been made to increase the size of the magnet and of the pot, but these increases result in proportional increases in the defects described. Attempts have also been made to form the speaker pots of a U-shaped strip of material, but such strips have proven inefficient in actual use.

It is the object of the present invention to provide a speaker pot which is generally oval or ring-shaped and is formed of an integral piece of tubing or the like. Such a pot is provided with no sharp corners to emit electromagnetic waves and is formed with no seams through which the electromagnetic waves must pass. As a result high efficiency may be obtained with a minimum of cost.

A feature of the present invention lies in the fact that due to the efficiency with which the electromagnetic waves may flow through the speaker pot, a minimum of electromagnetic force is lost and the efficiency of the speaker is considerably increased.

2

A further feature of the present invention resides in the provision of a speaker pot which may be formed of a short length of extruded metal which is generally oval in shape or may be formed by flattening the opposed sides of a short length of cylindrical seamless tubing. As a result my speaker pot may be formed at extremely low cost and is highly efficient.

These and other objects and novel features of my invention will be more clearly and fully set forth in the following specification and claims.

In the drawings forming a part of my specification:

Figure 1 is a rear elevation view of my speaker showing the construction thereof.

Figure 2 is a bottom plan view of my speaker showing the outline shape of the speaker pot.

Figure 3 is a cross sectional view through my speaker showing the construction thereof.

Figure 4 is a detail view of the speaker pot removed from the speaker.

The speaker A is formed as best illustrated in Figure 3 of the drawings. A flexible diaphragm 10 formed of fibrous material is provided with a frusto-conical body 11 terminating at its outer extremity in a peripheral flange 12. A series of ring shaped corrugations 13 are provided in the flange 12 to permit ready flexibility of the diaphragm. A paper tube 14 is adhered to the rear surface of the frusto conical body 11 in communication with a central aperture in the diaphragm 10. A speaker coil 15 encircles the paper sleeve 14 and is held thereon by a suitable film of cement or adhesive. The coil supporting sleeve 14 is preferably of a single thickness of paper within the coil 15 and the coil itself is formed of extremely fine wire so that the entire sleeve 14 and coil 15 are of but a thickness of a few thousandths of an inch.

A speaker frame 16 is connected to the diaphragm 10 at the outer extremity thereof. This frame 16 is provided with a ring shaped outer extremity between opposite sides of which extend an integral bridge portion 17. The bridge portion 17 is off-set rearwardly from the marginal edge of the frame 16 so as to lie rearwardly of the frusto conical diaphragm body 11. The center of the bridge portion 17 of the frame is rearwardly bowed as indicated at 19 and is integrally attached to the speaker pot 20.

The speaker pot 20 is generally oval in shape and comprises a seamless metal oval of the necessary width to properly conduct the flux from the permanent magnet. A magnet 21 which may be either of the permanent magnet type illus-

trated, or which may be an electromagnet, is secured to the inner surface of the speaker pot 20 along one flat side 22 thereof. The opposite flat side 23 of the pot 20 is provided with an aperture 24 therethrough which aperture is of just sufficient diameter to accommodate the coil 15 mounted upon the sleeve 14. The coil 15 may move axially relative to the aperture 24, but is extremely close to the surface of the coil for maximum speaker efficiency.

A pole piece 25 is supported at one end of the magnet 21. This pole piece 25 is provided with an end 26 which is of proper diameter to fit within the sleeve 14. A gasket 27 is positioned between the pole piece 25 and the inner surface of the flat side 23 of the pot 20. The end 26 of the pole piece 25 is concentric with the aperture 24 and provides a ring shaped aperture between the pole piece and the walls of the aperture 24 which is of just sufficient width to slidably support the sleeve 14 and its coil 15.

The speaker diaphragm 10 is provided with a plug 29 of felt or suitable material for closing the central aperture thereof and to prevent dust and the like from entering the interior of the sleeve 14. A flexible diaphragm 30 also encircles the sleeve 14, being secured at its inner extremity to the diaphragm 10 adjacent the sleeve 14 and being secured at its inner extremity to the bridge 17 of the frame 16. Thus the coil 15 is sealed from dust or dirt, while at the same time the diaphragm 10 may flex freely in an axial direction.

It will be seen that the rounded ends of the pot 20 conduct electronic magnetic waves with a minimum of loss. The flux from the end of the magnet abutting the flat side 22 is conducted to the opposite side 23 of the pot 20. There are no seams in the member 20 to interrupt the flow and as a result the efficiency of the speaker is substantially improved.

My speaker may be supported by suitable supporting screws or bolts extending through apertures such as 31 extending through the ring shaped outer frame 16. A relatively thick gasket 32 of paper or the like may be interposed between the speaker frame 16 and the panel against which the speaker is mounted. A bracket 33 may be provided on the bridge 17 of the frame 16 on which the remaining structure of the speaker may be supported. The terminals of the coil 15 may be connected to bayonet type terminals 34 mounted on an insulation strip 35 on the bridge 17.

I have found that when a gap is provided in the speaker pot this gap effectively results in increasing the spacing between the pot and the magnet pole piece. By eliminating any such gap in the speaker pot, the effectiveness and efficiency of the speaker is greatly increased.

In accordance with the patent statutes, I have

described the principles of construction and operation of my speaker, and while I have endeavored to set forth the best embodiment thereof, I desire to have it understood that obvious changes may be made within the scope of the following claims without departing from the spirit of my invention.

I claim:

- 10 1. A speaker including a speaker pot, said speaker pot comprising a short length of seamless tubing having a pair of substantially parallel side portions and integral arcuate curved ends connecting the same, a magnet secured to one of said flat sides and extending toward the other, said magnet having a diameter slightly shorter than said parallel flat side portions, an aperture in the other of said sides in opposed relation to said magnet, a pole piece secured to said magnet and extending into said aperture in spaced relation to the walls thereof, and a hollow cylindrical gasket between said magnet and said other side wall.
- 15 2. A speaker comprising a speaker pot including a short length of seamless tubing having substantially parallel sides and integral arcuate ends, said flat sides being substantially equal in length to the diameter of said rounded ends, and an aperture through one of said flat sides located centrally thereof, a magnet axially aligned with said aperture and engaging the other of said flat sides, a pole piece having a relatively large diameter and in contact with said magnet and a relatively small diameter end coaxial with, and extending into, said aperture, and a hollow cylindrical sleeve interposed between the large diameter end of said pole piece and said apertured side.

DONALD C. CARLSON.
